HAIR CURLING DEVICE

Filed April 5, 1927

UNITED STATES PATENT OFFICE

ARNAUD E. PAUSSER, OF PHILADELPHIA, PENNSYLVANIA

HAIR-CURLING DEVICE

Application filed April 5, 1927. Serial No. 181,059.

This invention relates to improvements in hair curling devices, and more particularly in that class of device adapted to give what is known as a permanent wave and in which the hair is wound upon a rod or stem, and after being wrapped with a suitable chemical-containing wrapper is inserted in a heater.

The principal object of the present invention is to provide a novel device for holding the hair securely on the curler rod and for holding the wrapper securely in position around the hair. To the latter end, the invention contemplates the provision of a wrapper element including as a permanent part thereof means for holding the wrapper in position when the latter is wound around the hair upon the stem.

Broadly, the invention contemplates the provision of a novel wrapper in the form of a strip for use in conjunction with hair curling apparatus of the stated type and possessing as its principal novel characteristic an inherent tendency to hold its position when wound about the stem.

In the attached drawings:

Figure 1 is a view of a wrapper made in accordance with my invention;

Fig. 2 is a view in perspective of another type of wrapper embodying the same basic principle of the invention;

Fig. 3 is a view of a form of stem forming a part of the hair curling apparatus mentioned with a lock of hair wound thereon and held in place by means of a retaining strip or wrapper such as shown in Fig. 2;

Fig. 4 is a view of the stem with the wrapper shown in Fig. 1 wound in position about the hair, and

Fig. 5 is a view in perspective of a wrapping strip embodying a modification within the scope of the invention.

Referring to the drawings, Figure 1 illustrates a well known form of wrapper used in conjunction with hair curling apparatus and consisting usually of a flannel strip 1 adapted to be wound about the hair on the curler stem and impregnated with suitable chemicals which in conjunction with heat, commonly applied through the medium of a heater in which the curler stem is inserted,

acts to set the curl in the hair. Some difficulty has been experienced in the past in retaining these wrapper strips in position when wound around the hair on the stem, and it has been common practice in the past to employ rubber bands or like elements as retaining elements.

In the present instance, I form the strip 1 with one or more wires 2 extending longitudinally and preferably the entire length of the strip, as illustrated, this wire having the physical characteristics that will cause it to tend to retain any form into which it may be bent and having sufficient strength to hold this form against some slight pressure. In the form of strip shown in Fig. 1, the wire 2 is attached to one face of the strip by means of a thread 3 sewed into the strip 1 and over the wire 2 in a zigzag stitch, as clearly illustrated.

The same general principle may be applied to wrapping strips whose primary function is to retain the hair in position when originally wound upon the stem, as hereinafter described. A retaining strip of this character is shown in Fig. 2, and consists in a preferred form of a relatively short strip 4 of cheese cloth or other coarse fabric having one or more wires 5 of the type set forth above secured in suitable manner thereto, as for example by means of the stitching shown in Fig. 1.

In practice, the hair is wound upon a stem 6, as shown in Fig. 3, the lock of hair 7 being held at the scalp end by a suitable clamp 8 and being wound around the stem 6 as illustrated. The strip 4—5 when wound around the outer end of the lock 7, as shown in Fig. 3, is sufficient to retain the lock securely in the wound position without loosening. In practice, it is preferable that as the outer end of the lock is approached in the initial operation of winding upon the stem, the strip is introduced into the winding operation before the extreme end of the lock is reached, so that a substantial portion of the strip is wound on the stem with the hair and underlies a portion of the lock as well as overlying the extreme outer end, as illustrated. In this class of wrapper, it is sometimes of advantage to

apply an adhesive to the end of the strip, as indicated at 12 in Fig. 2.

Following the winding of the lock of hair upon the stem 6, the wrapper 1 is applied, as shown in Fig. 4, it being only necessary in this case to wind the strip in spiral convolutions around the lock of hair so that the hair is completely confined and covered by the strip. By reason of the presence of the wire 2 in the strip, the strip naturally retains its spirally wound form, and no separate securing means is required.

Strips of this character are particularly desirable for use in conjunction with hair winding devices of the general type shown in the Bongers Reissue Patent No. 16,558.

It will be understood that there is to be no restriction as to the particular manner in which the wires are attached to the strips, nor to the particular material of which the strips are made. When the strips are made of fabric, the wire-attaching means illustrated in Fig. 1 is highly satisfactory, although other means may be used. Should the strip be of paper or other material not lending itself readily to the reception of sewed stitches, the wire may be attached, for example, as shown in Fig. 5, in which the wire 9 is held in position on the strip 10 by means of a retaining strip 11 narrower in the present instance than the strip 10 and secured to the latter by suitable adhesive, the wire being confined between the strip 11 and the strip 10, as clearly illustrated.

I claim:

1. As a new article of manufacture, a wrapper for use in hair curling comprising an elongated narrow strip of flexible textile fabric adapted for winding longitudinally in convolutions around a hair-supporting stem, and a flexible metallic element attached to and extending longitudinally of the strip and having a characteristic tendency to retain the form into which it may be flexed.

2. As a new article of manufacture, a wrapper for use in hair curling comprising an elongated narrow strip of flexible textile fabric adapted for winding longitudinally in convolutions around a hair-supporting stem, and a flexible wire of small gage attached to and extending longitudinally of the strip and having a characteristic tendency to retain the form into which it may be flexed.

3. As a new article of manufacture, a wrapper for use in hair curling comprising an elongated narrow strip of flexible textile fabric adapted for winding longitudinally in convolutions around a hair-supporting stem, and a flexible metallic element attached to and extending longitudinally and centrally of the strip and having a characteristic tendency to retain the form into which it may be flexed.

4. As a new article of manufacture, a wrapper for use in hair curling comprising

an elongated narrow strip of flexible textile fabric adapted for winding longitudinally in convolutions around a hair-supporting stem, and a flexible metallic element secured by open stitches against a face of said strip longitudinally thereof and having a characteristic tendency to retain the form into which it may be flexed.

5. As a new article of manufacture, a self-securing hair-binding strip for hair curlers comprising a flexible fabric strip adapted for winding longitudinally about a hair-supporting stem, said strip having means confined entirely within the edges thereof for retaining said strip in the form into which it is wound whereby said strip is adapted to constitute a means for retaining a lock of hair in tightly wound condition upon the stem.
